UNITED STATES PATENT OFFICE

WILLIAM E. CHRISTMAN, OF PHILADELPHIA, PENNSYLVANIA, ASSIGNOR TO KELLEY AND HUEBER, OF PHILADELPHIA, PENNSYLVANIA, A COPARTNERSHIP COMPOSED OF J. MAURICE KELLEY AND JOSEPH U. HUEBER

SPECTACLE CASE

Application filed May 7, 1930. Serial No. 450,333.

My invention is particularly directed to providing novel means for stiffening and reinforcing a flexible case adapted to receive and contain spectacles and the like.

5 Flexible cases heretofore employed for such purposes, and usually comprising one or more pieces of leather or like material and an integral flap adapted to be folded over to close the case, have been provided with stiffening 55 means of various forms, in each of which, however, may be found disadvantages not arising in the present invention.

Thus, for stiffening such cases, a strip of metal bent roughly to U-shape has been utilized and provided intermediate its arms with a reinforcing block of wood or the like either secured to the strip by nails, rivets, gluing or other convenient means, or disposed within a recess formed by the metal strip and held in 20 place therein under compression of the metal strip and by the sides of the case; this block forms a support for one member of the snap or glove fastener used for closing the case.

These and other generally similar means 25 of reinforcing and stiffening a spectacle case have certain disadvantages, such as the plurality of steps required for their manufacture which makes the cost thereof unduly high, and also because the reinforcing block 30 to which reference has been made soon becomes broken or loosened from its proper position and thus not fully effective to perform its intended functions.

Among the purposes and objects of the 35 present invention, therefore, is to provide a novel reinforcing and stiffening means for the purposes aforesaid which may be easily and cheaply manufactured in large quantities; which is fully effective throughout long 40 life for the performance of its intended functions, and which is of strong and durable construction and thus substantially indestructible even under abnormally severe conditions of use.

45 A further object of the invention is to provide a spectacle case of the class described having stiffening and reinforcing means made entirely of metal and adapted to be readily inserted within the case and as readily removed therefrom when desired, and

which affords adequate support for the cooperating members of the snap or glove fastener usually employed for fastening the case and negatives any danger of breakage to the spectacles or other fragile article contained 55 within the case when the case is being fastened as well as at other times.

A further object of my invention is to provide a reinforcing means as aforesaid which is operative to support the bridge or nose 60 piece of a pair of spectacles when the latter are disposed in the case, and is cooperative with integral stiffening means to maintain desired stiffness and rigidity of the case.

Other objects, purposes and advantages of 65 my invention will be hereinafter more particularly mentioned or apparent from the following description of a preferred embodiment thereof, reference being had to the accompanying drawings.

In the said drawings, Fig. 1 is a front elevation of a spectacle case of the class in which my invention may be employed showing the flap in closed position; Fig. 2 is a vertical section on the line 2—2 in Fig. 3 of a spectacle 70 case like that shown in Fig. 1 and embodying 75 a preferred form of the reinforcing and stiffening means of my invention; the flap of the case being open; Fig. 3 is a top plan view of the case shown in Fig. 2, and Fig. 4 is a side 80 elevation of my stiffening and reinforcing 85 means as shown in Fig. 2 and 3 removed from the case. In the several figures like characters are employed to designate like parts, and the sectional view referred to is taken in the direction of the arrows as indicated.

Referring now more particularly to the drawings, the spectacle case 1, which may be made of leather, imitation leather, cloth, or 90 any other material of desired flexibility, strength and durability, is of a usual form, and comprises, as shown, two pieces of the material 2, 3 secured together by a peripheral seam 4 or otherwise as desired, a portion 95 of the piece 2 forming a flap 5 adapted to be folded down over the other piece 3 and to be secured in folded or closed position by a snap or glove fastener comprising the usual co-operative male and female members 6, 7. 100

It will be understood that I have herein shown and described a spectacle case of this form for purposes of example only, and that my improved reinforcing and stiffening means as hereinafter described may be employed with equal facility with other types of cases.

The stiffening and reinforcing means of my invention adapted to be employed in a case of the form to which I have referred comprises a single, integral strip of spring steel or other suitable metal, the width of the strip being substantially equal to the transverse width of the space included between the parts 2 and 3 of the case. This strip is preferably bent as shown in Fig. 4 to provide side arms 11, base 12 and reinforcing convolutions 13 which thus form a plurality of adjacent bights or loops intermediate the side arms. The side arms 11 before the device is inserted into the case, are outwardly divergent toward their free ends and form obtuse angles with the base, which latter extends oppositely inwardly and upwardly from the side arms toward the convolutions 13 when the device is viewed as in Fig. 4.

The reinforcing and stiffening means when formed as just described is adapted to be inserted into the case for operative assembly therewith in such manner that the arms 11 lie within and parallel to the side edges thereof while the base lies along the bottom of the case, thus placing the strip under compression at the corners and also at the center reinforcement, the loops of which are also compressed somewhat, as clearly shown in Fig. 2, whereby the side arms are held tightly against the inner edges of the case and exert sufficient stress thereagainst to maintain the case in rigid stretched condition while the edges of the strip maintain the side walls of the case in suitably spaced transverse relation as shown in Fig. 3. The convolutions 13 of the reinforcement 13 are thus positioned between the walls of the case substantially beneath the flap fastener and serve to resist the thrust on the front wall of the case and prevent it from collapsing when the female member 7 of the fastener is snapped over the male member 6, while the outer faces of the reinforcement are adapted to receive the bridge or nose-piece of the spectacles and hold the latter in their proper position in the case when the flap is closed; the case is therefore prevented from collapse from front to back at all times by the operation of the reinforcing and stiffening means, while the latter also serves to properly hold the spectacles or eyeglasses in place as well as to constantly maintain the case in properly distended condition.

As before pointed out, the reinforcing and stiffening device of my invention is cheap to manufacture and, being formed entirely from

a single integral strip of metal, is devoid of attached parts which are liable to work loose or break when the case in which the device is disposed is in use. The device, moreover, is extremely sanitary and may be readily removed from the case for sterilizing or cleaning when desired and as readily replaced therein.

It will be understood that the particular design of the reinforcing and stiffening means comprised in my invention may be varied from that shown and described herein to adapt it for employment in spectacle cases of different forms, and further that the particular configuration of reinforcing loops or bights may also be varied as desired irrespective of the specific design of said means as a whole, without departing from the spirit and scope of the appended claims.

Having thus described my invention, I claim and desire to protect by Letters Patent of the United States:

1. The combination with a case provided with a flap and cooperative fastening means carried by the case and flap respectively, of a reinforcing and stiffening strip disposed within the case and provided with a plurality of oppositely extending convolutions disposed in operative alignment with said fastening means when the case is closed.

2. The combination with a case comprising front and rear walls secured together at the sides and bottom, a flap operative to close over the front wall and a fastener comprising cooperative male and female members respectively carried by the case and the flap, of an integral reinforcing and stiffening element disposed within the case and comprising side arms operative to lie adjacent the side edges of the case, a base lying adjacent the bottom of the case, and a plurality of convolutions extending upwardly from the base adjacent its midpoint into the case and operative to form a support for a pair of spectacles disposed within the case and for the male member of the fastener.

3. A reinforcing and stiffening element for a spectacle case or the like comprising an integral strip of resilient material bent to form a pair of oppositely divergent side arms, base members extending oppositely inwardly from the side arms, and a plurality of convolutions integral with the base members substantially equidistant from the side arms and adapted for transverse compression when the element is disposed in the case.

4. A reinforcing and stiffening element for a spectacle case or the like comprising a single strip of resilient metal bent to form a pair of side arms, base members extending oppositely inwardly from the side arms and a plurality of convolutions disposed substantially equidistant from the side arms and extending generally normal to the base, the side arms

being oppositely outwardly divergent from the adjacent base members and the latter extending in opposite angular relation to each other from the side arms toward the convolutions.

5 In witness whereof I have hereunto set my hand this 6th day of May, 1930.

WILLIAM E. CHRISTMAN.
